UNITED STATES PATENT OFFICE

HARRY E. KAPLAN AND BERNARD L. BOUER, OF CHICAGO, ILLINOIS

TELEPHONE PAD ATTACHMENT

Application filed March 14, 1929. Serial No. 346,911.

This invention relates to telephone pad attachments and it has for its object to provide means for slidably mounting a pad consisting of memorandum sheets, index or directory sheets, or advertising sheets on the base of a telephone desk set to be accessible while using the telephone as well as at other times.

Another object of the invention is to provide a pad attachment which can be easily mounted on the base of a telephone desk set in a convenient and inconspicuous position and where it will not interfere with the use of the receiver while still being accessible for use by one using the telephone.

And a further object of the invention is to provide a pad attachment which is adapted to be used as a base for the telephone desk set and in which the pad is slidably mounted so that it can be adjusted for extending the pad into operative position at any point about the telephone.

We have illustrated the invention in a selected embodiment in the accompanying drawings in which

Fig. 1 is an elevation showing the invention embodied in a telephone desk set of the French or cradle type with the pad slide extended in position for use.

Fig. 2 is a top plan view of the attachment with the pad slide extended.

Fig. 3 is a bottom plan view of the attachment.

Referring to the drawings our invention is shown applied as a base to the support of a telephone desk set. We have shown it applied to the support 4 of a telephone desk set of the French or cradle type but it can be just as well applied to the old fashioned desk set in the same manner. The invention comprises a cylindrical base 5 which has a bottom plate 6 and a supporting plate 7, the latter being located below the top of the base to form a seat for the bottom of the support 4 of the telephone desk set. This support is provided with a bottom cushion 8 which fits snugly in the seat in the base. The support 4 of the French or cradle type of telephone desk set is not lifted like the old fashioned desk set when the telephone is used and no

fastening devices are required for securing the base to the support, but when the invention is applied to a telephone desk set of the old fashioned type it will be desirable to provide screws or other suitable means for securing the base to the support of the desk set so that it will be carried with the support in the use of the telephone. Suitable cushion buttons 9 may be provided on the bottom plate to engage a desk or table upon which the telephone is placed. The base has a slot 10 to receive the pad carrier 11 which is slideable through the slot into closed position as indicated in broken lines in Fig. 2, and also in Fig. 3, and into open position Figs. 1 and 2. 55 This carrier has button guides 12 on its bottom, which may be in the form of screws, and which travel in guide slots 13 in the bottom plate to guide the pad carrier and limit the movement thereof. The pad carrier has 60 upstanding sides 14 and an overhanging flange 15 to receive and hold a pad 16 and it also has a handle 17 to facilitate the movement of the carrier. Tubular holders 18 are 65 arranged in the base to receive pencils 19 alongside the sliding carrier in convenient position for use.

The invention is made of a size and shape to neatly fit and form a base for the support of a telephone desk set and it can be 70 made of metal or any other material suitable for the purpose and harmonize in color and general configuration with that of the telephone set. The invention does not in any way interfere with the mechanical or electrical parts of the telephone desk set and the carrier can be operated while the set is being used. The base can be adjusted to any position relative to the support so that the desk set can be used in the usual manner and the 75 invention can be adjusted as required for accessibility.

It is the primary intention to provide a pad on the slideable carrier for ordinary memoranda and this pad may carry advertising or other printed matter. Or the pad may be in the form of a small telephone directory or index or it may be made up in any form and for any purpose. The pad is 80 fitted on the carrier between the sides 14 and 85 90 95 100

is held in place by the flange 15 and new pads may be easily inserted as required.

We have shown the invention in a simple form which is entirely satisfactory for the purpose but changes in the material and in the form, construction and arrangement of parts may be made without departing from the spirit or sacrificing the advantages of the invention, and we reserve the right to 10 make all such changes as fairly fall within the scope of the following claim.

We claim:

15 An attachment for a telephone desk set comprising a circular member including a bottom wall and an annular upstanding wall, said bottom wall having parallel slots therein, tubular guide members adapted to hold pencils therein extending across said circular member as chords of the circle thereof and 20 connected at spaced points to said annular wall, said guide members being parallel to said slots, said circular member having an opening therein, a slide movable through said opening and disposed between and 25 guided by said guide members, and button guides on said slide disposed in said slots to limit the movement of said slide through said opening.
